W. E. EDWARDS,
TOBACCO PIPE STAND,
APPLICATION FILED JULY 10, 1919.

1,429,228.

Patented Sept. 19, 1922.

UNITED STATES PATENT OFFICE.

WILLIAM E. EDWARDS, OF IRVINGTON, NEW JERSEY.

TOBACCO-PIPE STAND.

Application filed July 10, 1919. Serial No. 309,807.

To all whom it may concern:

Be it known that I, WILLIAM E. EDWARDS, a citizen of the United States, and a resident of Irvington, in the county of Essex 5 and State of New Jersey, have invented new and useful Improvements in Tobacco-Pipe Stands, of which the following is a specification:

This invention relates to a tobacco pipe 10 stand or support which will hold or support the bowl of a tobacco pipe in an upright position upon a flat surface whereby a filled and lighted pipe may be set upon a table or like support without danger of the tobacco 15 ashes being spilled upon the table and injuring the same.

The objects of the invention are to provide a device of the character described which is simple and inexpensive in its construction; which can be applied to a pipe of any shape or configuration and support the same in an upright position; which can be permanently secured to and sold as a part of a pipe, or which can be made separately and detachably or interchangeably used upon a number of pipes; which can be swung into an inoperative or out-of-the-way position along the stem of the pipe when the pipe is being smoked so as not to mar the 30 appearance of the pipe in any way; which is positively held in an operative or inoperative position; and which attains other advantages and results as may be brought out in the following description.

Referring to the accompanying drawing in which like numerals of reference indicate the same parts throughout the several views,

Figure 1 is a side elevation of a conventional tobacco pipe having a stand or support constructed in accordance with the invention permanently applied thereto;

Figure 2 is an end view thereof;

Figure 3 is an enlarged detached perspective view of the stand or support shown 45 in Fig. 1;

Figure 4 is an enlarged vertical longitudinal sectional view through the ferrule or attaching band;

Figure 5 is a horizontal sectional view 50 through the same;

Figure 6 is a detached perspective view of the supporting arm or frame;

Figure 7 is an enlarged detached perspective view of the modified form of the attaching ferrule or band which can be detachably applied to a pipe stem;

Figure 8 is a side elevation of another shape of tobacco pipe, showing the detachable support or stand applied thereto;

Figure 9 is an end elevation thereof; 60

Figure 10 is a side elevation of a tobacco pipe of another shape, showing the detachable stand in operative position for supporting the pipe; and

Figure 11 is a similar elevation showing 65 the stand in an inoperative position.

Specifically describing the embodiment of the invention illustrated in Figures 1 to 6, inclusive, the reference character A designates a conventional tobacco pipe of the well-known curved stem type, comprising the bowl B and curved stem C. Substantially

every pipe is provided with a metallic ferrule or band 1 on the stem between the bowl and the bit thereof as an ornamentation. 70

It is contemplated by one form of the invention to use this conventional ferrule or band 1 as an attaching member for the stand, prop or support 2. To this end the ferrule 1 is provided at one end thereof 80

with an integral downturned wing 3 which is rolled upwardly to form a pivot sleeve 4 which extends transversely of the pipe stem C, the outer ends of the sleeve 4 being provided at the lower sides thereof 85

with outwardly curved extensions 5, as shown in Figures 3 and 5. This pivot sleeve 4 serves as the means for attaching the supporting prop 2 to a pipe. This supporting prop 2 comprises a substan-

tially U-shaped piece of spring wire having the arms 7, the free ends of which are formed with the inwardly bent portions 8 into opposite ends of the pivot sleeve 4, as shown in Figure 3. The other end of the 90

prop 2 is curved or arched, as at 9, and bent in a plane at an angle to the arms 7. When 95

in an operative position the prop 2 is swung forwardly toward the bowl B of the pipe, and the uppermost point in the arch 9 en-

gages the bottom of the pipe, the junction points 10 of the arch 9 and arms 7 forming spaced feet which rest upon the table or the like on opposite sides of the longitudinal 100

median line of the pipe to support the pipe 105 in an upright position and prevent it from falling over. The pivot ends of the arms 7 of the frame tend to spring inwardly and the curved extensions 5 of the sleeve 4 back of the arms 7 and cooperating with this

spring action, will positively hold the frame 110 2 in operative position. The arch 9 is shaped

to conform to the stem of the pipe, and when in an inoperative position the prop 2 is swung rearwardly so that the arms 7 straddle the stem C of the pipe and the arch 9 partially 5 fits around the stem, as shown by dotted lines in Figures 1 and 2. As the prop is swung rearwardly the curved extensions 5 of the sleeve 4 spread the arms 7 and as the arms pass by these extensions the spring action of 10 the arms will cause them to snap back against the ends of the sleeve 4 and on the other side of the extensions 5 to positively hold the prop 2 in an inoperative position and close to the stem of the pipe so as to 15 be out of the way. The extensions 5 thus serve as detents for holding the prop 2 in both operative and inoperative positions.

It is an important feature of the invention that the device may be also made and 20 used as an attachment to a conventional pipe, so as to be adapted to be applied to old pipes or new ones which are not supplied with the device as above described. For this purpose the attaching ferrule is in 25 the form of a split spring ring 12, as shown by Figure 7. The construction of the attaching ferrule or band is otherwise as described above in connection with Figures 1 to 5, inclusive, comprising the pivot sleeve 30 13 and curved extensions 14. The supporting prop 2 is interchangeable with either the permanent solid ferrule 1 or the split spring ferrule 12, the construction of the whole stand being identical with that shown 35 by Figures 1 to 6, inclusive, with the exception that the attaching ferrule is detachable, of a split ring formation and separate from the usual ornamental ferrule on the pipe stem. This detachable construction is 40 shown as applied to a straight stem pipe D in Figures 8 and 9, and to a curved stem pipe E in Figures 10 and 11.

It is to be understood that the attaching ferrules may be of various configurations, 45 such as circular, elliptical or square, to fit various shapes of pipe stems, and that the supporting props may be bent or shaped to conform to the different configurations of the pipe stems so that the pipe will be supported in an upright position when the prop 50 is in operative position, and the frame will fit closely to the pipe stem when the stand is in an inoperative position. A pipe having a stem of square cross-section is shown 55 in Figures 10 and 11 and it will be understood that the attaching ferrule 12 would be square in shape, and that the arch 9 of the prop 2 could be pointed, or a right angle,

to conform to the stem of the pipe, when the frame is in its inoperative position as 60 shown in Figure 11.

Various detail modifications and changes may be made in manufacturing the device without departing from the spirit and scope of the invention, and I do not wish to be 65 understood as limiting myself except as required by the following claims when construed in the light of the prior art.

Having thus described the invention, what I claim is:

1. A tobacco pipe support having a prop formed of a single piece of wire with a pair of spaced arms adapted to be pivoted at their free ends to a pipe stem so that the prop will swing longitudinally thereof, said 75 arms being connected at their other ends by an arch extending out of the plane of the arms and adapted at one end of the swing of said arms to receive the pipe stem within its bend and allow the support to fold compactly thereagainst and at the other end of the swing of said arms to abut against the stem of the pipe and hold the prop away from the same in supporting position with the junction points of said arch and arms 80 serving as feet to engage a supporting surface at opposite sides of the median line of said pipe.

2. The combination with a tobacco pipe, 90 of a prop hinged thereto to swing longitudinally of the pipe stem, said prop adapted at one end of its swing to fit close against the pipe stem and at the other end of its swing to project therefrom in supporting position, and a detent for holding said prop against 95 the pipe stem in each of said positions.

3. In a tobacco pipe support, the combination of a member adapted to be applied to a tobacco pipe, said member having a pivot sleeve extending transversely of the pipe 100 which said sleeve is provided at each end thereof with an extension, a supporting prop comprising a pair of spring arms pivotally mounted in the ends of said pivot sleeve, said arms engaging a supporting surface to 105 hold the pipe in an upright position when the arms are swung to one side of the pivot into operative position and said arms lying closely against the pipe when swung on the opposite side of the pivot into inoperative 110 position, the arms springing over the said extensions at the ends of the pivot sleeve as they swing from one side to the other and said extensions thus holding the prop in both operative and inoperative positions.

WILLIAM E. EDWARDS.
